CHARLES E. HANNY, OF UNIONVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT

AUTOMATIC ELECTRIC SWITCH

Application filed July 21, 1928. Serial No. 294,518.

My invention relates to the class of switches - ordinarily known as entrance switches and particularly to the type intended for general public use in residences, offices, apartment houses, etc.

Switches of this type have usually consisted of a metal box having a hinged cover and enclosing a switch and fuses and having an external operating handle.

10 The covers of these boxes have usually been merely latched in closed position so as to permit the ready opening of the same by the tenant in order to insert or replace blown fuses.

15 The results of this type of construction have been far from satisfactory because, for instance, the entire switch construction being free of access, the tenant is strongly tempted to over-fuse the installation or to add new circuit lines and thus overload the circuit to such an extent that the fuse receptacles or clips cannot receive fuses of large enough capacity to properly protect the circuit. In the event of the fuses blowing re-

20 peatedly, the tenant is strongly tempted to (and sometimes actually does) bridge the fuse terminals with coins or other metal objects, thus endangering not only the various electric devices in the circuit but also causing a tremendous fire risk by the over-heating of wires, arcing at imperfect joints, short circuits, etc.

25 Further, the tenant, in most instances, must furnish his own fuses and, the average person knowing little of such matters, may purchase fuses of such small capacity that they will blow repeatedly or he may install fuses of greater capacity than the installation is intended to carry and thus endanger both life and property.

30 In these days of the rapidly increasing introduction of new electric household and office devices, it is the rule rather than the exception, for the general public to thoughtlessly add more and more new devices and attach them in one way or another to circuits which may already be loaded to maximum capacity. Thus it is highly desirable that the circuit be protected by an automatic switching device inaccessible enclosed in a

locked box and having an external handle for normal manual operation, the automatic portion of the construction being calibrated by central service station attachés and being normally inactive but functioning to entirely 55 open the circuit on overload or short circuit conditions.

My invention aims to provide the combination of a manually operated switch for normal operation and a normally inactive 60 automatically operated auxiliary switch for protection against overload or short circuits.

One object of my invention is to provide an enclosed switch construction having an external operating handle, a manually operable switch for normal operation and a normally inactive auxiliary switch adapted to automatically open the circuit on either a gradual overload, a sudden excessive surge 65 in the circuit or a short circuit. 70

Another object is to provide an automatic safety switch which will not require the use of fuses or other replaceable parts and which may be calibrated by the central station employees and then locked or sealed so as to 75 prevent access to any of the switch parts or terminals by the current consumer.

Another object is to provide a construction of this character which will have sufficient time lag to prevent the automatic operation 80 of the switch by the usual surge in the circuit caused by the initial closing movement of the switch.

Another object is to provide, in a construction of this character, a combined heater unit and electromagnet so associated with a bimetallic thermostatic latch as to cause the automatic operation of the latch but without any current flowing through the latch. 85

Another object is to provide a combined 90 heater and electro-magnetic coil of the preceding description directly in the circuit to be controlled but of such carrying capacity as to offer practically no resistance to a normal current flow. 95

Neither of the switch members need be of any exact type but I have chosen to incorporate my invention in a construction similar to that shown in the Getchell Patents Nos. 1,677,334 and 1,677,335. 100

Detailed descriptions and differences will be further disclosed as the specification proceeds.

In carrying out the invention in the preferred manner, I provide an insulating housing which carries the various conducting elements. The latter includes a manually operable main switch for normal operation and a quick-break switch for automatic operation, the automatic switch preferably having an auxiliary contact. This quick-break switch is held in closed circuit position by means of a latch which is not included in the electric circuit but which is adapted to be thermostatically operated by reason of a gradually increasing overload and which is adapted also to be instantaneously operated electro-magnetically by a sudden excessive overload.

The unit which includes the housing, the switch and the latch mechanism is adapted to be enclosed in any suitable manner in an outlet or switch box such, for instance, as is shown in the Getchell patents previously referred to.

The switch is designed to be opened either manually or automatically and the auxiliary switch is adapted to be reset or closed by the normal manual opening movement of the external switch handle.

Fig. 1 is a longitudinal sectional view of one form of apparatus embodying my invention, showing the manual and automatic switches in the open circuit positions in full lines and, in dot and dash lines, showing the manually operable switch member, and the automatic switch members in position for resetting the automatic switch.

Fig. 2 is an exploded perspective view of parts of the switch embodying my invention.

Fig. 3 is a detail view showing the thermostatic latching member engaged with a part of the automatic switch member to latch the latter member in closed circuit position.

The stationary post 5 is secured to the insulating body or housing 6 by means of a screw 7, and supports the main switch blade 8 on the pivot pin 9. The stationary contact or jaw 10 of the switch is secured to the body 6 by screw 11 which also secures in place the line terminal 12. The switch blade 8 is preferably adapted to be manually operated by means of a crank arm or rod 13 under all normal conditions.

The circuit terminal 14 is secured to the opposite end of the insulating body 6 by a screw 15.

The stationary contact plate 16 is secured to the body 6 by means of a screw 17. The bracket 18 is secured to the insulating body by means of screws 15 and 17.

The movable contact member 19 is pivotally supported by an arm of the frame 20 which is in turn carried by the pivot pin 9.

The arm 21 is also pivoted on pin 9 and is

provided with a contact roller 22 adapted to coact with the contact plate 16.

The cross bar 24 which is secured to the arms 21 is electrically connected by strip 25 to the stationary switch base 5. The contact member 19 is similarly connected by a flexible strip 26.

A spring 27 is interposed between the insulating body 6 and the rear end of the contact member 19 so as to apply pressure tending to move the two movable switch contact members 19 and 22 away from the stationary contact plate 16.

A pin 28 connected to the contact member 19 extends thru the cross bar 24 and is surrounded by a spring 29 which tends to draw the contact member 19 toward the arm 21.

The bimetallic thermostatic latching member 30 is riveted or otherwise suitably secured to bracket 18 and has its movable end adapted to engage the latch carried by the tilting frame 20. This latch has an abutment 31 and a movable abutment 32. A screw 33 serves as a convenient means for adjusting or calibrating the abutment 32 which projects more or less beyond the abutment 31, thus making it possible to adjust the sensitivity or point of release of the thermostatic member 30.

To reset the switch or close the circuit from the position shown in Fig. 1 the manually operable switch blade 8 is moved toward the dot and dash position. The pressure of the switch blade 8 against the cross pin 35 of the tilting frame 20 moves the frame to the dot and dash position of Fig. 1. This compresses the spring 27 and forces the lefthand end of the movable switch member 19 into engagement with the stationary contact plate 16.

This movement also carries with it the pin 28 and compresses the spring 29 so as to move the contact arm 21 and bring the contact roller 22 into engagement with the stationary contact plate 16, thus placing both of the springs 27 and 29 in compression. This movement brings the tip of the latch 32 into engagement with the tip of the thermostatic member 30 as shown in Fig. 3 and thus latches the members of the automatic switch in the closed circuit position.

When the auxiliary switch is latched in closed circuit position the manually operable knife blade switch 8 may be closed and the entire circuit completed thru the elements 12, 10, 8, 5, 25 and 26, 22 and 19, 16, 17, 18, 42, 40, 41, 15 and 14. Obviously the circuit can be opened manually when desired by moving the switch blade 8.

In series with the circuit thru the switch is the coil 40, the terminal plates of which, 41 and 42, are separated by an insulating washer 43. This coil is preferably covered with asbestos insulating material so as to insulate the individual coils and to retain the heat.

The two elements 44 and 45 constitute respectively the armature and the core of the magnet coil 40. The armature 44 is secured to the warping thermostatic latch bar 30, 5 preferably in such manner as to leave the bar 30 free to warp or bend when heated.

The core member 45 may be secured to the insulating cover 46. The latter is preferably provided with a hood-like portion 47 having 10 a recess or pocket 47' which surrounds the coil 40 but preferably leaving some open space for the radiation of the heat from the coil. Preferably this cover 46 and the hood 47 are formed of insulating material of an 15 asbestos character and the pocket is so positioned as to concentrate the heat of the coil adjacent the bendable portion of the bimetallic thermostat member 30.

The cover 46 may be suitably secured in 20 place for instance by a number of screws 48 extending thru anchorage members 49 into the body 6 or some element such as a nut carried thereby.

In case the circuit is slowly overloaded the 25 coil 40 will heat up the adjacent thermostatic bar 30 and release its tip from the latch 32 and thus allow the switch to open automatically. In case the circuit is suddenly and excessively overloaded the magnet coil 40 will 30 instantaneously draw the armature 44 toward the core 45 and bend the bar 30 so as to release the switch and automatically open the circuit.

By adjusting the screw 33 the switch may 35 be calibrated to open automatically under any desired overload condition.

After the auxiliary switch has once been set or calibrated, the box may be locked or sealed and then, so far as the current consumer is concerned, the device is positively 40 limited to carry only a certain predetermined load and will automatically open the circuit as soon and as often as the predetermined capacity is exceeded and regardless of any 45 attempt to prevent or delay the automatic operation.

It will be noted that, in this construction, the normal operation requires nothing more than the manual operation of the switch 50 blade 8 in exactly the same manner as a common enclosed switch for the reason that the automatic auxiliary switch is adapted to remain closed at all times except when automatically released by either the thermostatic latch or by the electro-magnetic coil.

When the auxiliary switch has been opened automatically it may be re-set or re-latched by the simple switch opening movement of the blade 8, but the complete circuit cannot 55 be re-established until the auxiliary switch has first been re-latched in this manner, after which the main blade 8 may be closed to complete the circuit. This last feature is of great importance because the auxiliary switch contacts are of the butt type and,

being concealed from the operator's vision, there would otherwise be great danger of fitting the contacts by uncertain jiggling movements or by leaving the contacts in any other than a perfect contacting position with 70 respect to the stationary contact.

Although this construction provides for the automatic operation of a bimetallic thermostatic latch, the latch itself is not in the circuit to be controlled. Some of the advantages of this are that there can be no arcing at the latching point as the latch is released—there is no danger of injuring the latch by a short-circuit or excessive overload—the number of electrical joints is reduced—fewer operations are required to produce and assemble the parts, therefore the cost is reduced and, by reason of there being fewer parts, the device is more dependable because there is less likelihood of the parts moving 85 or loosening and thus disturbing the calibration to which the device has been set.

I claim:

1. A switch including an insulating housing, a movable switch member, a thermostatic latch for said switch member, a stationary coil enclosed in said housing adjacent said latch for heating and bending said latch and for magnetically attracting said latch to release said movable switch member. 90

2. A switch including an insulating body, a movable switch member supported thereby, a thermostatic latch member for said switch member and having a magnetic armature secured thereto, a heat retaining cover for said body, and a coil enclosed by said body and cover for heating said latch member and also for magnetically attracting said armature on predetermined overload conditions and a core member secured in the cover in 105 proximity to said armature.

3. A switch including a manually operable main switch member, an auxiliary switch member, in series therewith, a catch for the auxiliary switch member, a bendable thermostatic latch for holding said catch and said auxiliary switch member, means of connection between the manually operable main switch member and the auxiliary switch member whereby said catch may be reset by the action of the manually operable main switch member, and a coil for electro-magnetically and for thermally bending said latch to release said auxiliary switch. 110

4. The combination in a quick-break switch 115 of a spring-pressed switch member, a bendable thermostatic latch for holding said switch member in closed position and an electro-magnetic coil in series with said switch and electrically independent of the latch, said latch being operable both thermally and magnetically by said coil, the said bendable latch being entirely free of circuit windings and free of the circuit controlled 125 by the switch. 130

5. The combination with a quick-break switch of a thermally bendable element for latching said switch in closed position and a magnetically operable release device having a coil in electrical circuit with said switch for heating said element and having an armature directly associated with said element and cooperating with said coil to release said switch on excessive overload in the circuit, 10 the said bendable latch being normally free of direct contact with said coil.

6. The combination in a quick-break switch of a bendable bimetallic latch normally holding the switch in a closed circuit position, 15 an electro-magnet coil in series with the switch for automatically heating and bending said latch to release the switch on an ordinary overload, and an armature carried by said latch and adapted to be attracted by 20 said magnet in the event of an excessive overload in the circuit, the said bimetallic latch and said armature being normally free from said coil.

7. The combination in a switch of a movable switch member, a spring for moving said switch member to open position, a bendable thermostatic latch for holding said switch member in closed circuit position, and a coil having both electro-magnetic and heating characteristics in series with said switch 25 and cooperating with said latch to bend said latch gradually by heat radiation or instantaneously by electro-magnetic action, the said thermal latch being entirely free of circuit 30 windings.

8. In an automatic switch construction the combination of a main switch and an auxiliary switch cooperating therewith, an adjustable catch for said auxiliary switch, a bendable latch cooperating with said catch to hold 35 said auxiliary switch in closed position, a magnetic coil for thermally bending said latch to release said auxiliary switch and for electro-magnetically bending said latch to 40 release said auxiliary switch, the said bendable latch being independent of the circuit 45 and free of all circuit winding.

9. In a switch construction the combination of a pivoted frame, a spring-pressed 50 contact member hinged to said frame, a secondary pivoted contact member, a resilient connection between said contact members providing limited relative movement between the same, a latch member coacting with said 55 frame to hold said frame and its contact members in closed circuit position, a combined electro-magnet and heating coil for disengaging said latch member on a prolonged overload, and for disengaging said 60 latch member on a sudden predetermined excessive overload.

10. A switch construction comprising an insulating body having a recess, snap action 65 switch mechanism having manually operable means on one side of the body for opening

and closing a circuit, a bimetallic latch member in said recess for holding the switch mechanism in its closed circuit condition, an armature member secured to the latch member, and a stationary coil serving to warp the latch when heated and serving to magnetically attract said armature when quickly overloaded.
